UNITED STATES PATENT OFFICE.

OSCAR WIEDEMAN, OF NARBERTH, PENNSYLVANIA.

METHOD OF AND APPARATUS FOR FINISHING STRAW HATS.

Application filed June 3, 1921. Serial No. 474,706.

To all whom it may concern:

Be it known that I, OSCAR WIEDEMAN, a citizen of the United States, residing at Narberth, in the county of Delaware and 5 State of Pennsylvania, have invented certain new and useful Improvements in Methods of and Apparatus for Finishing Straw Hats, fully described and represented in the following specification and the accompanying drawing, forming a part of 10 the same.

This invention relates to methods and apparatus for finishing straw hats. The invention aims to produce a better finished 15 product than is secured with the finishing methods heretofore employed, while at the same time effecting a great saving in labor, time and space as compared with former methods.

20 Heretofore it has been the usual practice to finish straw hats, whether hand-shaped by ironing over an internal form or machine-shaped in a hydraulic press or otherwise, by placing the shaped hat on an internal form, placing over it a damp cloth and ironing lightly with a hot iron. In the shaping of the hat the straw braid is 25 crushed or flattened so that the surface has an unnatural and undesirable appearance. The finishing process is for the pur-

30 pose of overcoming this flattened condition of the straw by raising the surface of the straw braid and restoring it more or less to its original and more pleasing appearance. This restoration of the condition 35 and appearance of the straw results from the moistening of the straw by the steam produced by the application of the hot iron to the damp cloth in the customary method

40 of finishing above referred to. This method of hand finishing requires skilled labor and is slow and expensive, and is otherwise unsatisfactory. The steam from the damp cloth softens the straw at the tip edge, or 45 square, of the crown as well as elsewhere in the tip and crown sides, and because of this softening of the tip edge the sharp edge or angle produced in the shaping of the hat is more or less lost; also, this method 50 of finishing is apt to result in a sagging or bulging of the central part of the tip of the hat, and the cloth used frequently leaves a mark on the braid.

55 In accordance with my method of finishing straw hats, the outer surface of the

shaped hat is steamed to raise the flattened braid with portions of the hat, and more especially the tip edge and adjacent portions of the tip and crown sides, covered to protect them from direct access of the 60 steam, and the hat is then dried with the tip held flat under light pressure insufficient to crush and flatten the braid again. The drying is effected most desirably with the hat placed upside down in a heated 65 shallow external form which provides a flat plate for the tip and a flange extending about the side of the crown adjacent the tip edge, a tip weight placed inside the hat serving to hold the hat in position with 70 the tip pressed lightly against the bottom of the form. The tip weight has most desirably a bottom pad of soft rubber or other suitable yielding and extensible material the edge of which presses outwardly 75 lightly against the crown side adjacent the tip edge.

The invention thus eliminates altogether the ironing of the old finishing method 80 which was slow and expensive, involving the use of skilled labor and requiring relatively much space. The invention produces a finished hat which is free from the above-mentioned defects of hats finished by the ironing method.

85 The invention also includes the feature of protecting the portion of the side of the crown on which the ribbon band is to be placed from the steam so that the surface of this part of the hat is not restored but remains in the flattened and relatively smooth condition resulting from the shaping of the hat. The finished hat thus has a suitable relatively smooth surface for receiving the band, and the use of the customary lining of paper or other material to protect the band from the rough straw is avoided.

90 The apparatus which I have invented to facilitate the carrying out of the new method includes a heated external form adapted to fit the tip and the adjacent portion of the side of the crown of a straw hat, and a tip weight. The external form is most desirably made of two separable 100 parts, a bottom plate which may be heated in any suitable manner, and a ring for use to protect the edge of the tip from the steam as well as serving as a part of the external form. The tip weight is provided 105

110

at its bottom with a pad of soft material of a shape to fit within the crown of the hat against the tip. The material of which the pad is made should be soft and extensible and most desirably also elastic. I have found soft rubber a suitable material for the pad.

In order to give a full understanding of the invention, I will describe in detail 10 the devices embodying the apparatus feature of the invention illustrated in the accompanying drawings, and the finishing of hats in accordance with my method. In said drawings:—

15 Fig. 1 is a perspective view of the bottom plate;

Fig. 2 is a perspective view of the ring;

Fig. 3 is a perspective view of the tip weight;

20 Fig. 4 is a fragmentary vertical section of the tip weight showing one of the bolts connecting the pad to the metal portion of the weight;

25 Fig. 5 is a sectional elevation of the ring showing the position of the hat therein during the steaming; and

Fig. 6 is a sectional elevation of the entire apparatus showing the position of the hat therein during drying.

30 The apparatus shown in the drawings includes an external form 10 adapted to engage the outer surface of the tip of a straw hat and the outer surface of the side of the crown adjacent to the tip, and best made 35 of metal. The form is made of two separable parts, a ring 11 and a bottom plate 12. The ring 11 is formed to provide an upwardly extending side flange 13 and an inwardly extending horizontal or bottom flange 14. These two flanges form a rectangular corner at their line of juncture 15, which is shaped to fit the edge of the tip of the hats to be finished. The ring 11 is provided with a handle 16.

40 45 The bottom plate 12 has at its periphery a horizontal supporting flange 17. In the central portion of the bottom plate 12 is the contact surface 18 which is raised above the supporting flange 17 by a distance equal to the height of the bottom flange 12 of the ring 11 and is of a shape corresponding to that of the inner edge of the flange 12. When, therefore, the ring 11 is placed 50 on the bottom plate 12 as shown in Fig. 5, the contact surface 18 of the bottom plate and the upper surface of the bottom flange 12 of the ring lie in the same plane and provide a continuous bottom for the form.

55 Means are provided for heating the external form 10 through the bottom plate 12. Any suitable heating means may be used for this purpose, but a steam box 19 as shown in Fig. 5 is desirable as it serves to maintain the plate 12 at a substantially constant and uniform temperature. The

bottom plate 12 may be held in position by studs 21 on the steam box fitting into recesses 20 in the plate.

The tip weight 30 is provided at its bottom with a soft pad 31, most desirably of 70 soft rubber and secured by means of bolts 33 whose heads 34 are vulcanized into the pad. The bolts pass up through holes 35 in the metal portion 32 of the weight and are secured by nuts 36. The pad 31 extends 75 slightly beyond the edges of the metal portion of the tip weight, the periphery of the pad being such that the pad just fits within the crown of the hat in connection with which it is to be used. The pad is most desirably sufficiently soft and extensible so that the pressure caused by the weight of the metal part 32 tends to cause the pad to extend laterally in all directions. Consequently, when the tip weight is placed in 80 the hat as indicated in Fig. 5, the edge of the pad lightly presses or holds the side of the hat crown adjacent the tip edge against the side flange 11 of the form, while the lower surface of the pad presses the tip 90 gently against the bottom of the form. The pad should not be substantially thicker than the height of the side flange 13 of the ring 11.

95 In finishing a hat according to my method with the apparatus illustrated and described, the procedure may be as follows:—A hat which has been shaped under pressure in a hydraulic press or otherwise, and which may also have been passed 100 through a brim press, the braid of the entire hat having been crushed flat, is placed upside down with its tip edge, or square, in the ring 11. When the hat is so placed, the ring 11 covers the outer surface of the tip edge and a narrow portion of the crown sides and of the tip adjacent to the edge. Before the pad is placed in the ring 11, the ring is heated to about the boiling 105 temperature of water, preferably by leaving it in place on the heated bottom plate 12. The ring 11 with the hat supported thereon is held over a steam pot or other source of supply of live steam (Fig. 5). The steam strikes the unprotected outer surface of the hat, and in so doing raises the eyes and other parts of the flattened braid and restores the braid more or less to its 110 original condition. The moisture absorbed from the steam by the straw will penetrate somewhat through the straw into the portions of the tip and crown side surfaces which are covered by the ring 11, so that there will be no line of demarcation apparent on either the crown or the tip between 115 the portion covered by the ring and the portion directly exposed to the steam. The moisture does not, however, reach to the extreme edge of the tip sufficiently to affect 120 the sharpness given to this edge in the shap- 125

ing of the hat. The fact that the ring 11 is heated prevents condensing of the steam on the ring.

The steaming takes only a few seconds, 5 and the ring 11 with the hat in it is then placed on the bottom plate 12 so that the hat is then in the heated external form made up of the bottom plate 12 and the ring 11. The tip weight 30 is then placed 10 in the hat (Fig. 6). The pressure of the tip weight applied to the part of the hat in the external form through the pad 31 serves to press the tip and the adjacent portion of the side of the crown against the external 15 form with a gentle force sufficient to hold the tip flat and the tip edge square during the drying of the hat. The fact that the pressure is applied through the soft pad 31 into which the eyes of the braid 20 on the inner surface of the tip and the crown side, which have been raised by the steaming, may penetrate, lessens the tendency with some straws of the contact with the form to flatten down the raised outer 25 surface of the braid.

When the drying has been completed, which may take about five minutes, the tip weight is removed from the hat and the finished hat is then removed from the external 30 form. The ring 11 has during the drying been reheated by its contact with the plate 12 and may be immediately used again to support another hat over the steam pot.

Hats finished by the method described are 35 attractive in appearance, as the braid over the entire outer surface of the hat is so far restored to its original condition that it has no crushed or flattened appearance. At the same time the edge of the tip is sharper 40 and more square than in hats finished in the old way.

In finishing hats as above described, and in former methods of finishing, the braid is raised and restored to a relatively rough 45 condition over the entire outer surface of the hat including the lower portion of the side of the crown which is to be covered by the hat band. Such a rough surface is, however, not suitable for receiving the ribbon 50 hat band as it spoils the appearance of the ribbon, and in order that the ribbon shall lie smooth it has heretofore been customary to place a band of heavy paper or like material around the hat under the ribbon of 55 the hat band to protect the ribbon from the roughened braid of the hat. I avoid the need for such a lining for the hat band by so finishing the hat that the braid of the portion of the side of the crown which is to be 60 covered by the hat band remains in the flattened condition which it has after the hat is shaped and before it is steamed for finishing.

This is done in accordance with my invention 65 by covering the lower portion of the

side of the crown during the steaming of the hat so as to protect this portion of the surface from the steam. Such covering is most desirably accomplished by means of a tight-fitting water-proof band 40 such as an elastic rubber band, of the same width when applied to the hat as the hat band to be applied to the hat. The band 40 is placed on the crown of the hat before the hat is steamed and is retained in place on the hat until the 70 drying is completed. When the band 40 is thus used, the braid on the portion of the finished hat about which the hat band is to go will be left flat and smooth just as it came from the hydraulic press or other 75 shaping means. The hat band will lie smooth on a hat so finished without any paper or other lining.

What is claimed is:

1. The method of finishing stiff straw hats 80 after they have been shaped and pressed which comprises raising the braid which has been crushed in the pressing by steaming the outer surface of the hat with a portion of the surface covered to protect it from direct access of the steam.

2. The method of finishing stiff straw hats after they have been shaped and pressed which comprises raising the braid which has been crushed in the pressing by steaming 90 the outer surface of the hat with a portion of the surface covered to protect it from direct access of the steam, and thereafter applying gentle pressure to the tip to hold it flat during the drying of the hat.

3. The method of finishing stiff straw hats after they have been shaped and pressed which comprises raising the braid crushed in the pressing by steaming the outer surface of the hat with the tip edge covered to protect it from direct access of the steam.

4. The method of finishing stiff straw hats after they have been shaped and pressed which comprises raising the braid crushed in the pressing by steaming the outer surface of the hat with the tip edge covered to protect it from direct access of the steam, and thereafter gently pressing the tip against a heated surface.

5. The method of finishing straw hats after they have been shaped and pressed which comprises raising the braid crushed in the pressing by steaming the outer surface of the hat with the lower portion of the side of the crown covered to protect it from access of the steam, and thereafter drying the hat.

6. The method of finishing stiff straw hats after they have been shaped and pressed which comprises raising the braid which has been crushed in pressing by steaming the outer surface of the hat with the tip edge and the portion of the tip and crown side immediately adjacent to the tip 125 130 135

edge protected against direct access of the steam, and thereafter gently pressing the tip and the portion of the crown side adjacent to the tip edge outwardly against a heated external form to dry the hat.

7. The method of finishing stiff straw hats which have been shaped and pressed, comprising raising the braid crushed in the pressing by steaming the outer surface of the hat with the tip edge and the lower portion of the crown side covered to protect them against direct access of the steam, and thereafter applying gentle pressure to the tip to hold it flat and keeping the lower portion of the crown side well covered until the hat is dry.

8. The method of finishing straw hats, which comprises steaming the outer surface of the hat with the tip edge and the portions of the tip and crown side immediately adjacent the tip edge protected from direct access of the steam and with the lower portion of the side of the crown covered and thereafter gently pressing the tip and the portion of the crown side adjacent to the tip downwardly and outwardly against a heated external form.

9. The method of finishing stiff straw hats after they have been shaped and pressed which comprises raising the braid crushed in the pressing by steaming the outer surface of the hat, and thereafter gently pressing the tip between a hot plate and a yielding surface so as to hold the tip flat while it is drying without recrushing the braid.

10. The method of finishing stiff straw hats after they have been shaped and pressed which comprises raising the braid crushed in the pressing by steaming the outer surface of the hat, and thereafter gently pressing the tip and a portion of the crown side adjacent to the tip between a heated external form and a yielding surface.

11. The method of finishing stiff straw hats after they have been shaped and pressed

which comprises covering the tip edge and the portions of the tip and crown side immediately adjacent the tip edge by placing the hat in a flanged ring, steaming the outer surface of the hat while in said ring, and thereafter retaining the hat in the ring and gently pressing the tip against a heated plate.

12. Apparatus for use in finishing straw hats, comprising an external form consisting of a bottom plate having a peripheral supporting flange and a raised central contact portion and a removable ring having an internally extending bottom flange and an upwardly extending side flange, said ring being adapted to rest on the supporting flange of the bottom plate with the upper surface of its bottom flange surrounding, and in the same plane with, the contact surface of the bottom plate.

13. Apparatus for use in finishing hats, comprising an open form-retaining, supporting and protecting ring having a narrow inwardly extending bottom flange and a narrow upwardly extending side flange adapted to receive the tip edge of a straw hat and to fit against and cover the portions of the tip and crown side adjacent to the tip edge while leaving the remainder of the tip and crown side uncovered so that they may be steamed.

14. A tip weight for use in finishing straw hats, comprising a body portion forming a weight and a pad secured to the bottom of the body portion and adapted to fit into the crown of a hat against the tip, said pad being of soft material and laterally extensible under the pressure of the weight of the body portion.

In testimony whereof I have hereunto set my hand in the presence of two subscribing witnesses.

OSCAR WIEDEMAN.
